US0D1009576S

(12) **United States Design Patent** (10) **Patent No.:** **US D1,009,576 S**
(45) **Date of Patent:** **** Jan. 2, 2024**

(54) **GRILL PRESS**

(71) Applicant: **Yangjiang Yangdong Xingtai Hardware Wooden Manufacture LLC**, Yangjiang (CN)

(72) Inventor: **Guixing Liu**, Yangjiang (CN)

(73) Assignee: **Yangjiang Yangdong Xingtai Hardware Wooden Manufacture LLC**, Yangjiang (CN)

(**) Term: **15 Years**

(21) Appl. No.: **29/831,872**

(22) Filed: **Mar. 23, 2022**

(30) **Foreign Application Priority Data**

Mar. 16, 2022 (EM) 008886261-0001

(51) **LOC (14) Cl.** **07-04**

(52) **U.S. Cl.**

USPC **D7/669**; D7/672; D7/682

(58) **Field of Classification Search**

USPC D7/354, 359, 368, 372, 393, 395, 401.2, D7/403, 407, 408, 409, 414, 500, 601, D7/602, 614, 629, 653, 664, 665, 667, D7/668, 669, 670, 672, 673, 674, 678, D7/681, 682, 694, 697, 703; D8/18, 34, D8/40; D21/455

CPC F23H 17/12; A47J 37/00; A47J 43/281; A47J 37/10; A47J 37/06; A47J 36/027; A47J 37/108; A47J 43/18; A47J 37/067; A47J 43/28; A21C 9/068; A21C 15/007; B25G 1/10; A22C 7/0076; A22C 9/008; B26B 25/005

See application file for complete search history.

(57) **CLAIM**

The ornamental design for a grill press, as shown and described.

DESCRIPTION

FIG. 1 is a perspective view of a grill press, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

1 Claim, 8 Drawing Sheets
